UNITED STATES PATENT OFFICE

2,670,959

SHOOTING GALLERY

Daniel N. Broyles, Knoxville, Tenn.

Application July 28, 1950, Serial No. 176,485

4 Claims. (Cl. 273—101)

1

This invention relates to improvements in amusement devices, and more particularly to a device in the nature of a shooting gallery provided to test the skill in shooting, as well as for entertainment or amusement of the user thereof.

Shooting galleries as provided heretofore generally have been in the nature of a large area having provision for movable targets to test the skill of the user, or have required extended range both as to length of space and lateral width thereof to increase the skill of the user or to provide for amusement or entertainment. It has not been practical with such devices as provided heretofore for installation thereof in relatively small space, as in a store, bowling alley or other building of amusement, whereby this may be added to the amusement features otherwise available.

One object of this invention is to provide a shooting gallery adapted to accommodate a single shooting implement with target, which composite device requires relatively small space or area and yet provides the amusement or training resulting from the use of a firearm.

A further object of the invention is to provide an entertainment or amusement device which will make possible the discharge of a firearm in association with a target while confining the effect thereof to relatively small space, without danger to surrounding objects.

These objects may be accomplished according to one embodiment of this invention by the provision of a housing which is associated with a tube or tunnel in which the firearm may be discharged, with provision therein for receiving the projectiles from the firearm. It is preferred that a cushion be provided at the end of the tube or tunnel to absorb the projectiles, such as may be formed by a layer of sand in the bottom of the tube. It is also preferred that a suitable target be arranged in the tube or tunnel with provisions for changing after a suitable period of use. One feature of this invention involves the manner in which the target is moved lengthwise in the tube or tunnel from the open end thereof to a suitable position for use, this movement being accomplished by gravity under control of the operator or user by a winding operation.

One form of the invention is illustrated in the accompanying drawings, in which:

Fig. 1 is a side elevation of the device;

Fig. 2 is a cross section through the tube or tunnel thereof on the line 2—2 in Fig. 1;

Fig. 3 is a front end elevation thereof;

Fig. 4 is a longitudinal sectional view through the lower end of the tube or tunnel;

2

Fig. 5 is a detail longitudinal section of the target-moving cylinder, with parts in elevation;

Fig. 6 is a cross section therethrough;

Fig. 7 is a view similar to Fig. 3 but partly in section, on the line 7—7 in Fig. 8;

Fig. 8 is a vertical cross section therethrough on the line 8—8 in Fig. 7;

Fig. 9 is a detail cross section through a portion of the tube or tunnel, showing the target holder in elevation;

Fig. 10 is a longitudinal sectional view therethrough; and

Fig. 11 is an enlarged side elevation of the target holder detached.

15 The device is adapted for use as a shooting gallery or range to practice the shooting of firearms, and may be used for amusement purposes or for training. In the form illustrated, the device is shown as constructed with an upright housing 1, from the upper end of which a tube or tunnel, generally indicated at 2, extends downwardly in an inclined direction. These parts may be assembled as a unit either in the shape shown or in such other relation as may be desirable. They are of sufficient height and length, respectively, suitably to accommodate an average-sized person and a reasonable extent of projection of the shot being fired, but the length of the tube or tunnel 2 may be varied for different types of firearms. It is preferred that the device be portable for ready handling and movement when desired, and, accordingly, the members 1 and 2 are shown as mounted on rollers 3 which may be in the form of casters or otherwise, as desired.

20 25 30 35 The upright housing 1 is constructed with opposite side walls 4, a front wall 5, and a top enclosure, generally designated at 6. Joining the upright front wall 5 and the top enclosure 6 is an inclined wall 7 from which the tube or tunnel

40 45 50 55 2 extends downwardly at an acute angle substantially normal to the plane of the inclined wall 7. The forward end of the tube or tunnel 2 is open at the face of the inclined wall 7, as shown in Figs. 3 and 8, and is preferably enclosed within a channel or molding, generally indicated at 8.

This tube or tunnel 2, preferably, is formed of sheet metal bent into cylindrical shape and extending downwardly from the wall 7 to the lower end of the device, having a flat bottom adapted to rest directly on the floor or to be supported by one of the casters 3. This tunnel 2 has an access or clean-out door 9 in the lower end portion thereof hinged to a side of the tunnel, or otherwise movably connected there-

with for access to the interior of the tunnel, as shown in Fig. 4.

The bottom of the tunnel 2 is adapted to receive an absorbing material, generally indicated at 10, which, in the form shown, preferably is composed of a layer of sand of sufficient thickness to receive and absorb the projectiles fired through the open upper end of the tunnel. A layer of perhaps five inches or six inches of sand usually will be sufficient for this purpose. A baffle 11 is shown extending from side to side in the tunnel 2 (see Figs. 2 and 4) to assist in bracing the lower end of the tunnel and to maintain the sand in proper relation thereto.

It is preferred that the interior of the sheet metal tunnel 2 be lined with a suitable sound-absorbing material, generally indicated at 12. One form of sound-absorbing material which has been found suitable for this purpose is a fairly heavy wall-board type known as "Celotex," made in strips and secured adhesively or otherwise to the interior of the cylindrical tunnel, preferably extending substantially throughout the circumference thereof, as shown in Figs. 2 and 7.

Provision is made for supporting a target within the tunnel 2, as generally indicated at 13 and shown in Figs. 4 and 7 to 11. The target 13 is adapted to be detachably secured by a spring clamp 14 to a holder 15, whereby the target may be slipped easily into or out of the holder but will be retained frictionally by spring pressure in the holder when the device is in use. It is preferred that means be provided for moving the target 13 up and down in the tunnel 2 so as to locate the target in the desired position, or make it accessible to the user at the upper end of the tunnel. Accordingly, I have provided a trolley 16 connected with the holder 15 and supporting the latter as shown in Figs. 9 and 11. The trolley 16 is mounted slidably in a track 17 that extends lengthwise of the tunnel 2 and is secured in suitable manner to the interior of the latter, as indicated in Fig. 9. The track 17, preferably, extends along the upper wall of the tunnel 2 and is shown as in sufficiently inclined relation so that the weight of the trolley 16 and holder 15 will be sufficient to move the latter downwardly along the track by gravity to allow for placing the target 13 at the desired position adjacent the lower end of the tunnel 2. The track 17 preferably extends downwardly to a point adjacent the door 9 to permit of insertion of the trolley 16 into the track through the open doorway. The track 17 is bridged at one end by a plate 17' (Fig. 8), which limits movement of the trolley 16 in an upward direction.

The trolley 16 is adapted to be moved upward and downward in the track 17 by means of a flexible cable, generally indicated at 18, which cable is secured at one end to the trolley 16, while the opposite end thereof extends around a guide roll 19 and upwardly in the portion 6 of the housing to a winding drum or roller 20. As shown in Fig. 6, the cable 18 is attached to the drum 20 by a pin or hook, generally indicated at 21 and located within an indentation in the drum. This will form a positive connection of the cable with the drum to prevent accidental separation therefrom.

The winding drum 20 is mounted loosely on a shaft 22 that extends through the drum and through the head portion 6 of the housing. The shaft 22 is journaled on bearings 22' in the end walls 4 of the housing. A crank 23 is provided on

the outer end of the shaft 22, as shown in Figs. 1 and 3, for rotation of the shaft to turn the drum. The drum 20 has a head 20^a fixed thereto at one end while the opposite end of the drum is closed by a head 20^b pinned to the shaft 22, to limit movement of the drum relative to the shaft in one direction.

The turning movement of the drum 20 is accomplished upon rotation of the shaft by a collar 24 (Fig. 5) adjustably secured to the shaft 22 and acting through a coiled spring 25 sleeved over the shaft 22, which coiled spring 25 is interposed between the collar 24 and the adjacent end of the drum 20. One end of the spring 25 bears against the collar and the other end bears against the adjacent end flange 20^a of the drum, whereby a frictional and yieldable connection will be provided between the collar and the drum that will cause rotation of the drum upon rotation of the shaft. However, slippage is permitted when the trolley 16 has been moved to an extreme position at one end of the track 17 so as to prevent breakage of the cable 18. The collar 24 is fixed to the shaft 22 in an adjustable position to vary the tension on the spring 25.

A spring 26 is also shown as interposed between one of the bearings 22' and a collar 24' also adjustably fixed in the shaft 22, tending to maintain the shaft in proper position according to the adjustment of the collar thereon.

While the device may be used with any suitable type of firearm, it is shown as having a rifle 27 connected therewith, and preferably, is attached by a chain or other secure but flexible connection with the device so as to prevent removal of the rifle from the interior of the tunnel 2, while allowing for ready movement thereof within the range of firing positions. Normally the rifle or other firearm is supported on a front ledge, generally indicated at 28, extending transversely of the open end of the tunnel and upon a rear ledge 29 extending transversely thereof at a point spaced from the open end, as shown in Figs. 7 and 8. Each of the ledges 28 and 29, preferably, has a notch intermediate the length thereof to facilitate resting or support of the rifle when not in use.

A shelf or shield is shown at 30 extending transversely of the tunnel 2 from the upper edge portion of the ledge 29 as a cover over an illuminating lamp 31 mounted on the bottom of the tunnel. This lamp 31, preferably, is directed toward the lower end of the tunnel 2 and should be disposed so as to illuminate the target 13 at its normal position in the lower end of the tunnel.

Additional lamps are shown at 32 in the head portion 6 of the housing 1 to illuminate a sign or other advertising feature, generally shown at 33 in said head portion.

Located in the front wall 5 of the housing 1 is a door 34 shown as hinged or otherwise movably supported in the housing. This door, preferably, is locked securely to prevent unauthorized access to the interior of the housing. A receptacle 35 is provided on the door adapted to receive targets which may be removed therefrom for use in the device.

Mounted on the door 34 on the inner side of the housing 1 is a bracket 36 upon which is supported a dispensing device, generally designated at 37. The dispensing device 37 is adapted for the dispensing of cartridges, either singly or in multiples as desired, and may be constructed substantially in accordance with the application of

Daniel Broyles and Calvin Russell for Vending Machines, Serial Number 17,274, filed March 26, 1948, now Patent No. 2,621,096, granted December 9, 1952. Such application is referred to for a more complete disclosure of the structure and manner of operation of the dispensing device 37.

This dispensing device 37 is held in place on the inner face of the door 34 by means of swivel bolts 38 (Fig. 8) in the example illustrated, although any suitable means may be provided for a secure support thereof within the housing 1. A receptacle 39 is located beneath the dispensing device 37 to receive the coins.

In the form of dispensing device set forth in the above-mentioned application and patent, this is adapted for discharging three bullets into a receptacle 40 mounted on a support unit 41 in an opening in the door 34. A receptacle in the dispensing device 37 contains a quantity of bullets which are fed down step-by-step and discharged in suitable numbers into the receptacle 40. The discharge of the bullets is controlled by the rotation of a feed unit as set forth more fully in the application and patent referred to above.

As shown in Fig. 8, the lamp 31 is adapted to be connected with a source of electric current so as to provide for automatic illumination of the interior of the tunnel 2 whenever the device is to be operated or used. The lamp 31 is shown as connected with a source of electrical supply, including a cable 59 leading to a junction box 60 on a side of the housing 2. A separate cable 61 extends from the junction box to the lamps 32 in the head portion of the housing.

The operation of the device will be evident from the foregoing description of its construction. The user or operator initially withdraws a target from the receptacle 35 on the front of the housing 1 and inserts the target into the clamp 14. Then, upon rotation of the shaft 22 by the hand crank 23, the trolley 16 and support 15 are lowered along the trackway 17 to the lower end of the latter, where a suitable stop is provided in the trackway to hold the target in its set position.

Upon insertion of a coin, such as a dime for instance, into the opening 45, the slide member 43 may be pushed in a full stroke, after which it may be withdrawn. This coin-controlled device will be a conventional part and the operation thereof will vary somewhat depending upon the characteristics of this part. However, the device set forth is described as one example thereof.

In this form the initial insertion of the slide member 43 may be made in a backward direction. Then, upon return motion of the slide member 43 in an outward direction by the operator, the dispensing device 37 may be operated through a stroke sufficient to discharge the required number of projectiles, according to the setting of the dispensing device 37. In the example given here, three bullets will be discharged thereby.

These bullets will be dropped into the receptacle 40 by the dispensing device 37, from which they can be withdrawn by the operator and used successively in the rifle 27.

Normally, when the device is not in use, the rifle rests on the ledges 28 and 29 with its barrel pointed into the tunnel 2, where it should be confined by a chain, cable or other flexible device so that it cannot be withdrawn entirely from the interior of the tunnel.

With the target in place at the lower end of 75

the tunnel 2, as shown in Fig. 4, the user of the shooting gallery then would insert the cartridges, one by one, into the rifle 27 either as they are respectively shot, or, if a repeating rifle is used, all can be inserted at one time. The target 13 enables the user to test his skill as well as provide entertainment or amusement.

Then, upon rotation of the drum 20 by the crank 23, the target can be drawn upward to the front of the device for more careful inspection of the results of the shooting. Additional targets may be used to replace the one previously used, or several target areas may be provided on a single target, as indicated in Fig. 9, as desired.

15 It will be noted that the crank 23 may be rotated in either direction to withdraw the target to the front of the device, since the drum 20 may rotate either forward or reverse. Moreover, there is no danger of breakage of the cable 18 through excessive winding of the drum, since the clutch device 24—26 will allow slippage between the shaft 22 and the drum as soon as the trolley 16 has reached the front end of the track 17.

The foregoing statement as to the order of 25 operating the device is merely an example, and the steps may be varied as desired without requiring the precise order of steps as set forth.

In servicing and collecting from the machine, the door 34 may be unlocked and drawn forward 30 to permit removal of the receptacle 39. The dispensing unit 37, preferably, also is mounted on the door so that upon such forward movement, the top of the receptacle in the dispensing unit is available for the replenishment of the supply 35 of projectiles therein at the same time.

This device provides a compact, unitary and portable shooting gallery which may be used in places of amusement or entertainment, either for instruction or for amusement. The device is so 40 constructed that there is little likelihood of injury to persons around the shooting gallery, since the projectiles are confined to the interior thereof, and the wall of the tunnel 2 may be made of sufficiently strong metal that there is no danger 45 of an escaping bullet. The sand or other absorbing material 10 in the lower end of the tunnel effectively receives and retains the projectiles. Such a device can be moved readily, being handled by one or two men and transported in 50 a comparatively light truck.

While the invention has been illustrated and described in certain embodiments, it is recognized that variations and changes may be made therein without departing from the invention, except 55 as set forth in the claims.

I claim:

1. A portable shooting gallery comprising a downwardly inclined tunnel having an open upper end adapted to receive therein means for firing projectiles, supporting means for the tunnel mounting the tunnel on a supporting surface in said downwardly inclined position at a substantial angle to the horizontal, means in the lower end of the tunnel for receiving and retaining said projectiles, said means comprising a mass of particulate material lying loosely on the bottom of the lower end of the tunnel, a track extending downwardly along the top of said inclined tunnel substantially throughout the length thereof, a weighted target holder slidably mounted on said track and movable by gravity downwardly therealong to a point adjacent said material from a point adjacent the open upper end of the tunnel, a flexible device connected at one end with said target holder, and winding means adjacent the

open end of the tunnel connected with the opposite end of the flexible device for moving the target holder upwardly.

2. A portable shooting gallery comprising a tubular tunnel supported in a downwardly inclined position with its upper end approximately at shoulder level of a person in standing position and its lower end close to ground level, said lower end being disposed in a substantially horizontal plane, a layer of particulate material within said tunnel at the lower end thereof and arranged with its surface substantially horizontal, and means for supporting a target in the tunnel adjacent said layer of material.

3. A portable shooting gallery comprising a tubular tunnel having an open upper end adapted to receive therein means for firing projectiles through the tunnel, supporting means for the tunnel mounting the tunnel on a supporting surface in a downwardly inclined position with its open upper end approximately at shoulder level of a person in standing position and its lower end close to said supporting surface, said lower end being disposed in a substantially horizontal plane, means in the lower end of the tunnel for receiving and retaining said projectiles, said means comprising a relatively thick layer of particulate material having a substantially horizontal top surface and extending over substantially the entire area of the interior of the tunnel, and means for supporting a target in the tunnel adjacent said layer of material.

4. A portable shooting gallery comprising a tubular tunnel having an open upper end adapted to receive therein means for firing projectiles through the tunnel, supporting means for the tunnel mounting the tunnel on a supporting surface in a downwardly inclined position with its open upper end approximately at shoulder level of a person in standing position and its lower end close to said supporting surface, said supporting means including an upright housing con-

nected with the open upper end of the tunnel, means forming a rest for a firearm in said open upper end, said lower end being disposed in a substantially horizontal plane, means in the lower end of the tunnel for receiving and retaining said projectiles, said means comprising a relatively thick layer of particulate material having a substantially horizontal top surface and extending over substantially the entire area of the interior of the tunnel, and means for supporting a target in the tunnel adjacent said layer of material.
